M. M. REYNOLDS.
ROLLER SCREEN.
APPLICATION FILED NOV. 8, 1915.

1,206,141.

Patented Nov. 28, 1916.

UNITED STATES PATENT OFFICE.

MILFORD M. REYNOLDS, OF VAN WERT, OHIO, ASSIGNOR OF FORTY-FIVE ONE-HUNDREDTHS TO CHARLES A. JONES, OF VAN WERT, OHIO.

ROLLER-SCREEN.

1,206,141.

Specification of Letters Patent. Patented Nov. 28, 1916.

Application filed November 8, 1915. Serial No. 60,269.

To all whom it may concern:

Be it known that I, MILFORD M. REYNOLDS, a citizen of the United States, residing at Van Wert, in the county of Van Wert and State of Ohio, have invented new and useful Improvements in Roller-Screens, of which the following is a specification.

My present invention pertains to adjustable window screens of the roller type; and it contemplates the provision of a simple, inexpensive and easily installed and operated construction, and one in which the screen is drawn from the roller against the action of a spring and is adjustably fixed in the position desired by reliable means carried on the screen and constructed and arranged to coöperate with means on the window frame; said means on the screen being susceptible of being readily disengaged from the means on the frame when it is desired for the spring-actuated roller to take up the screen.

The invention also contemplates the provision of a casing constructed with a view of protecting the screen when the same is not in use, and also constructed so as to render easy the movements of the screen out of and into the casing.

Other objects and advantages of the invention will be fully understood from the following description and claims, when the same are read in connection with the drawings, accompanying and forming part of this specification, in which:

Figure 1 is a front elevation showing my improvement as properly installed, outside of a window. Fig. 2 is an enlarged detail section of the upper portion of the improvement, taken in a plane at right angles to Fig. 1. Fig. 3 is an enlarged, broken section, taken longitudinally of the casing and showing part of the screen roller and all of the anti-friction roller in elevation. Fig. 4 is a detail section of the lower portion or free end of the screen, illustrating the casing at said end and the adjustable fixing means in said casing. Fig. 5 shows in side elevation one of the brackets of the casing. Fig. 6 is a broken perspective of one of the combined guides and racks for coöperation with the screen and the before-mentioned adjustable fixing means. Fig. 7 is a detail vertical section taken through the casing at the free end of the screen and the mechanism in said casing.

Similar numerals of reference designate corresponding parts in all of the views of the drawings.

The screen 1 that I employ is flexible in character, and may in the discretion of the manufacturer be rendered fire-proof and water-proof in any approved manner without affecting my invention. The said screen is designed to be fastened at one end to and be taken up on a roller, hereinafter described, and the said roller may be located at any suitable point on the window frame 2, though I prefer to arrange it adjacent to the crown bar of the frame as shown in Figs. 1 and 2. The roller referred to is numbered 3 and is preferably of the same general construction as the conventional shade roller at present in general use, in that it is designed to be turned about its axis in one direction against the action of a torsion spring 4 and when released is designed to be turned in the opposite direction by the expansion of said spring. I would have it distinctly understood, however, that the specific construction of the spring-actuated roller is not of the essence of my invention, and that therefore said spring-actuated roller may be of any construction consonant with the general purpose of my invention without involving departure from the scope of my invention.

My invention contemplates the use of screens 1 of various width and rollers 3 of different lengths, according to the widths of the window frames to be fitted. I prefer, however, to employ an extensible casing for the screen and the roller; said casing being adjustable as to length in order that it may be expeditiously and easily accommodated to window frames of different widths. As shown in Figs. 1 and 3 the casing comprises telescopically-arranged sections 5 and 6; the said sections being provided with slots 7 for the passage of the screen and being equipped at their outer ends with brackets 8, notched at 9 for the engagement of fastening screws 10, Fig. 2. By comparison of Figs. 2 and 3, it will be seen that the casing is equipped with telescopically-arranged roller sections 11 and 12. From this it will be manifest that the roller which serves the important purpose of easing the movements of the screen into and out of the casing, is adjustable as to length in concert with the casing. It will be manifest that by simply loosening

the screws 10, and swinging the casing and brackets 8 outwardly, the brackets may be disengaged from the screws and removed with the casing.

- 5 Arranged against the inner sides of the side stiles of the window frame are the combined screen guides and racks 13, which extend from the frame sill up to a point adjacent to the casing, as shown in Fig. 1.
- 10 The said guides and racks are identical in construction, and therefore a detailed description of the one shown in Fig. 6 will suffice to impart a definite understanding of both. The guide and rack referred to is of 15 light sheet-metal and of channel-form, and its back wall 14 is shaped to form a rack. It will also be noted by reference to Fig. 6 that the combined guide and rack is provided at 15 with lugs in which are notches 16, 20 for the passage of fastening screws, this construction being preferable because after the said screws are slightly loosened, the combined guide and rack may be lifted out of engagement therewith.
- 25 The free end of the screen 1 is provided with a casing 17, the ends of which are disposed and movable in the channel guides 13. Movable rectilinearly in said casing 17 are latches 18, having shoulders 19 and notches 30, Fig. 4, and mounted on rivets 21 in said casing are springs 22 the outer arms of which are arranged to bear against the shoulders 19, as shown, so that said arms will tend to press the latches 18 outwardly. 35 Pivoted at 23 in position to engage the notches 20 are pawls 24, and connected to the latches 18 and the pawls 24, are cables 25 and 26, respectively. The cables 25 are carried over a guide 27, and then downwardly through an opening 28 in the casing, and are provided below the casing with a finger piece 29. The cables 26 are carried over a guide 30, and are likewise carried downwardly through the opening 28, and 45 are provided below the casing with a handle 31. Thus it will be seen that when the pawls 24 are engaged with the notches 20 of the latches 18, the said latches will be retained in retracted positions, and consequently the 50 screen may be drawn downwardly or permitted to move upwardly at the pleasure of the operator. When, however, the handle 31 is drawn downwardly to disengage the pawls from the latches, the latches will be 55 impelled outwardly by the outer arms of the springs 22, with the result that the screen will be adjustably and strongly secured in the position in which it is placed.
- 60 It will be manifest from the foregoing that the adjustable fixing means best shown in Fig. 4 is, at once, simple, strong and easily operated; and it will also be manifest that after an adjustable fixing of the screen, it is simply necessary when the screen is to 65 be moved, to draw the latches 18 inwardly

until the pawls 24 are seated in the notches, whereupon the screen will be rendered free to move either upwardly or downwardly. It will further be manifest that the adjustable fixing means in combination with the 70 spring-actuated roller will maintain the screen at all times in a taut state which is desirable because it tends to prolong the usefulness of the screen. The inner arms of the springs 22 bear against the pawls 24, as 75 shown.

While designed primarily for use on window frames, I desire it distinctly understood that my novel roller screen is adapted to be used on porches and other frames to 80 which it is applicable without departure from my claims.

Having described my invention, what I claim and desire to secure by Letters-Patent, is:—

85 1. In a screen construction, the combination of a frame, a spring-actuated roller mounted adjacent to one end of said frame, combined guides and racks connected with the side stiles of the frame, a screen movable in said guides and connected with and adapted to be wound on the roller, a casing connected with the free end of the screen and arranged with its end portions in the guides, spring-pressed latches guided in said 90 casing and arranged at their outer ends to engage the racks, spring-pressed pawls mounted in the casing and arranged to engage and hold the latches against outward movement, and means carried by the casing 95 for retracting the latches and other means also carried by the casing for disengaging the pawls from the latches.

2. In a screen construction, the combination of a frame, a spring-actuated roller 105 mounted adjacent to one end of said frame, guides connected with the side stiles of the frame and provided with racks at their backs, a screen movable in said guides and connected with and adapted to be wound 110 on the roller, a casing connected with the free end of the screen and open at its ends and having its ends movable in the guides, and spring-pressed means carried by said casing and movable through the open ends 115 thereof and into and out of engagement with the racks.

3. In a screen construction, the combination of a screen, a casing connected thereto and open at its ends, rectilinearly movable latches guided in said casing and having 120 shoulders and notches, pawls mounted in the casing and arranged to engage said notches, springs mounted in the casing and having outer arms engaging the shoulders of the 125 latches and inner arms bearing against the pawls, and cables connected with the latches and the pawls, respectively, and extending outside the casing.

4. In a screen construction, a roller cas- 130

ing, a roller mounted therein, a screen connected to the roller and movable into and out of the casing, and brackets fixed with respect to the end portions of the casing and disposed at right-angles thereto and each having notches at opposite edges, arranged out of alinement with each other.

5. In a screen construction, the combination of a suitably-supported spring-actuated roller, a screen connected to said roller, a fixed channel guide receiving one edge of the screen and having a rack at its back and and also having lugs provided in their lower edges with notches, means resting in said

notches and supporting and connecting the 15 channel guide to a support, and means carried by the screen and detachably engaging the rack of the channel guide to hold the screen against movement by the action of the spring-actuated roller. 20

In testimony whereof I have hereunto set my hand in presence of two subscribing witnesses.

MILFORD M. REYNOLDS.
